[57] CLAIM

The ornamental design for a table with an illuminated top, as shown and described.

DESCRIPTION

FIG. 1 is a plan view of a table with an illuminated top showing my new design;

FIG. 2 is a side view of the table shown in FIG. 1;

FIG. 3 is a bottom view of the table shown in FIGS. 1 and 2; and

FIG. 4 is an exploded perspective view of the table shown in FIGS. 1, 2 and 3.

The sides of the table not shown are the same in appearance as the side shown in FIG. 2.

FIG. 1.

FIG. 2.

FIG. 3.

Fig. 4.
